Des. 220,574
Patented Apr. 27, 1971

220,574

MODEL RACING CAR

Eric Harrison Broadley, Flackwell Heath, England,
assignor to Lola Cars Limited, Slough, England

Filed July 10, 1969, Ser. No. 18,168

Claims priority, application Great Britain Jan. 10, 1969

Term of patent 7 years

Int. Cl. D21—02

U.S. Cl. D34—15

FIG. 1 is a top plan view of the model racing car;
 FIG. 2 is a front elevation thereof;
 FIG. 3 is a side elevation thereof; and
 FIG. 4 is a rear elevation thereof.

The opposite side of FIG. 3 is identical to the side shown.

I claim:

The ornamental design for a model racing car, as shown.
